(57) **CLAIM**

The ornamental design for a handle for a shaving razor as shown and described.

DESCRIPTION

FIG. 1 is a front perspective view of a design of a handle for a shaving razor of the present invention;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken line disclosure of the razor cartridge illustrates the environment of the handle and forms no part of the claimed design. The remaining broken lines illustrate portions of the handle and form no part of the claimed design.
